UNITED STATES PATENT OFFICE

93,838

DESIGN FOR A BOOT OR SIMILAR ARTICLE

Charles Miller, Long Island City, N. Y.

Application September 27, 1934, Serial No. 53,408

Term of patent 14 years

To all whom it may concern:

Be it known that I, CHARLES MILLER, a citizen of the United States and a resident of the city of Long Island, county of Queens, and State of New York, have invented a new, original, and ornamental Design for a Boot or Similar Article, of which the following is a specification, reference being had to the accompanying drawing, forming part thereof.

In the drawing:

Fig. 1 is a perspective view of a boot showing my new design.

Fig. 2 is a side view of the boot.

The dominant feature of the invention resides in the ornamental effect produced by the contour of the upper portion of the leg of the boot, said upper portion comprising a cuff which is made of contrasting material to that of the leg of the boot. As here shown, said cuff is made of shirred velvet, or similar material and tapers upwardly.

I claim:

The ornamental design for a boot or similar article as shown and described.

CHARLES MILLER.
